BRAID CLAMP

Laurence F. Hofer, Oswego, Oreg.

Application January 28, 1955, Serial No. 34,283

Term of patent 14 years

(Cl. D54—13)

Fig. 1.

Fig. 2.

Fig. 1 is a front elevation view of a braid clamp showing my new design; and

Fig. 2 is a front perspective view thereof.

The broken lines shown in Fig. 2 are for illustrative purposes only.

I claim:

The ornamental design for a braid clamp, as shown and described.
